UNITED STATES PATENT OFFICE

130,401

DESIGN FOR A DESK

Jack Barofsky, Los Angeles, Calif.

Application August 25, 1941, Serial No. 103,012

Term of patent 14 years

To all whom it may concern:

Be it known that I, Jack Barofsky, a citizen of the United States, residing at Los Angeles, in the county of Los Angeles and State of California, have invented a new, original, and ornamental Design for a Desk, of which the following is a specification, reference being had to the accompanying drawing, forming part thereof.

The sides opposite those shown in the drawing are the same as the sides illustrated. All sides are substantially similar.

The back is plain.

The dominant features of my design are shown in solid lines in the drawing.

I claim:

The ornamental design for a desk, as shown and described.

JACK BAROFSKY.
